UNITED STATES PATENT OFFICE.

CLYDE A. CONNELLY, OF SHELBY, OHIO.

DOOR-OPERATING MEANS.

Application filed March 31, 1926. Serial No. 98,812.

My invention relates to door-opening and closing means permitting of a person effecting an opening or closing of the doors at a point somewhat remote therefrom.

5 The invention more particularly relates to the type of door-operating means shown in United States Patent No. 1,508,270, granted to me September 9, 1924, in which a switch is mounted on a post or the like distant from 10 a garage or other structure, the doors of which are to be opened and which includes an electric motor having operative connection with the doors as well as manually operable switches in circuit with the motor to 15 throw the motor into and out of action and to place the doors under the control of the operator.

The general object of my present invention is to provide a door-operating means 20 of the general type referred to improved in various particulars especially with regard to the means to operate a traveller from the motor as well as with respect to the circuit and the devices embodied therein.

25 The nature of my invention, its distinguishing features and advantages, will clearly appear as the description proceeds.

Reference is to be had to the accompanying drawings forming a part of this specification, it being understood that the drawings are merely illustrative of one example of the invention.

Figure 1 is a plan view of door-operating means embodying my present invention 35 showing the same associated with doors and a fragment of the structure illustrated in horizontal section;

Figure 2 is a side elevation of said door-operating means with an indicated circuit;

40 Figure 3 is an enlarged fragmentary view of a portion of the door-operating means with a cushioning device for the traveller in vertical section;

Figure 4 is an enlarged plan view given to 45 show the guiding means for the traveller as well as details of the door connections of the traveller;

Figure 5 is a view partly in plan and 50 partly in horizontal section showing the spring cushioning means for the door connecting rods illustrated in plan;

Figure 6 is an enlarged vertical section in the plane indicated by the line 6—6, Figure 3;

55 Figure 7 is an elevation of the upper portion of the outside post and its switch;

Figure 8 is a view of the device shown in Figure 7 but somewhat enlarged and with part of the casing broken away to show the interior arrangement of the switch; 60

Figure 9 is a plan of a circuit that may be employed, showing certain elements of the circuit in the positions when the doors are being opened;

Figure 10 is a view similar to Figure 9 65 but illustrating the automatic switch and relays when the parts are arranged for the closing of the door.

In the illustrated example of my invention the numeral 15 indicates a structure 70 which may be a garage or the like. The structure 15 is shown with swinging doors 16 to open and close by mechanism comprised in my improved devices. To each door is pivotally secured a rod 17, said rods 75 being convergent and connected at their inner ends with an element 18 advantageously in the form of an angle bracket, said element 18 having a stem 19 bolted thereto, said stem having a plunger 20 operating in 80 a cylinder 21. Springs 22 in cylinder 21 bear against opposite faces of a plunger 20. The cylinder 21 with the springs 22 and plunger 20 with stem 19 form an indirect connection between the head 18 and a traveller 85 23. Said traveller is driven by an endless chain 24, the illustrated connection being by a stud 25 on chain 24 and entering a vertical slot 26 in traveller 23, said stud having a roller 25'.

The chain 24 runs over an idler sprocket wheel and a driven sprocket wheel 28 driven in any suitable manner from the shaft on an electric motor 29, there being a reducing gear 30 conventionally indicated in the present example as the drive connection between the shaft 29 and driven sprocket 28. Said reducing gear is of well known form and does not constitute part of the present invention and therefore needs no further elucidation. The traveller 23 has a tubular guide bar 32 in a frame 33 which also mounts the motor 29. In practice, rods 17 have incorporated therein turnbuckles 117 for adjustment. 100

Frame 33 has a longitudinal switch shifting bar 34 mounted in the ends of the frame to have limited sliding movement thereby when said rod is tripped by traveller 23 as will appear. 105

Trip 35 is provided on bar 34 near one end and a second trip 135 on said bar near 110

the opposite end. A switch base 36 is disposed adjacent the rod 34 between two fingers 37 on said bar 34. To switch base 36 are pivotally secured two switch blades 38, 39, said blades having fixed pivots 40, about which the blades may rock. The switch blade 39 is adapted to have contact with switch leaves 41, 42 and the switch blade 38 is adapted to have contact with two switch leaves 43, 44 according to the direction in which the base 36 is moved by the fingers 37 on shift rod 34.

Relays 45, 46 are provided in circuit with motor 29; in said circuit also are pairs 15 of manually operable and normally closed switches 47 as well as manually movable switches 48. In the motor circuit also and remote from the doors 16, to be controlled by one approaching or leaving a garage, 20 for example, is a switch designated generally by the numeral 49 which is key-controlled, being provided with switch lock 50, the numeral 51 indicating a lock for the casing of switch 49. The switch 49 includes a 25 switch assemblage 62 having spaced terminal plates 52 and a bridge piece 53 fixed on a slide 54 adapted to be operated by the shift bar 55 actuated from lock 50. At the opposite side of shift bar 55 also is a second 30 switch assemblage 63 which provides an emergency stop for the doors and includes spaced terminals 56 and a slide 57 having a bridge piece 58. Slide 57 is subject to a spring 59 and slide 54 is subject to a spring 35 60. The spring 60 normally tends to maintain the switch open by maintaining the bridge piece 53 out of engagement with the terminals 52. Spring 59 normally maintains switch assemblage 63 closed. The switch 40 49 is here shown as mounted on a post 61. The switches 47 and 48 may be anywhere conveniently located about the structure 15.

With the above described assemblage, the traveller 23 serves to actuate the door-operating rods 17. With the initial movement 45 of said traveller 23 in either direction the force exerted by the traveller is absorbed by the springs 22 and upon compression of a spring, the movement of the cylinder 21 50 with the traveller will act on the plunger rod 19 and through the element 18 or equivalent connection, the rods 17 will be moved to swing the doors 16. As traveller 23 approaches a sprocket wheel 27 or 28, 55 a finger 123 on said traveller engages a trip 35 or 135 to shift rod 34 for making or breaking the circuit through the fingers 37 and the switch assemblage controlled thereby, thus throwing the motor in and out as 60 required for arresting the travel of chain 24 and traveller 23 after the completion of an opening or closing movement of the doors 16.

The operation will be readily understood 65 in connection with the showing of the illus-

trated circuit for carrying out the example of the invention shown. In the normal position of the parts when not in operation, the circuit is open at the armatures 145, 146 because the relays 45 and 46 are de-energized. 70 When the motor is not running and the described automatic switch controlled by the shifting fingers 37 is conditioned for an operation, either for opening the doors 16 or closing the same, after a previous operation, 75 then, the switch blade 39 may be engaged with switch leaves 41 and 42 and therefore in electrical connection with said leaves, or, 80 switch blade 38 may be engaged with the switch leaves 43, 44 and therefore in electrical connection with said leaves 43, 44. The switch blades 38, 39 are insulated from each other by the base 36 and operate without contacting with each other. The switch operating fingers 37 move the switch blades 85 simultaneously so that the blade 39 will contact with leaves 41, 42 or the blade 38 will contact with leaves 43, 44 as the case may be. Assuming that the doors 16 have been closed and therefore ready for the next operation, to wit, that of opening the doors, the relays 45 and 46 are de-energized and the switch is open at the armature 145 which is then out of contact with the magnet of relay 45 and therefore the circuit is 90 open at the armature 145. Also, the circuit is open at the armature 146 and the automatic switch blade 39 is in connection with contact leaves 41, 42. 95

To open the doors either of the switches 100 48, or the switch 62 may be operated to momentarily close the circuit therethrough by insertion of a key in lock 50. The circuit will then be from the positive lead *a* of the supply current through the closed switches 105 63 and 47 by wire *c* through the temporarily closed switch 62 or 48 to wire *d* and from wire *d* by wire *l* to switch leaves 43 and by wire *f* to and through switch leaves 41, 110 through blade 39 to wire *g* and to the winding of relay magnet 45 energizing said magnet and attracting the armature 145, bringing said armature into contact with the terminal *h* associated with the wire *d*. Hence, 115 the circuit will be closed between the armature 145 and said terminal *h* so that the current flows from wires *a* and *b* to the wire *d* which connects by wire *l* with switch leaves 43. It will be observed that at this time a circuit is established running from leaves 41 and blade 39 to and through switch leaves 42 and by wire *i* to switch leaves 44 and by wire *j* to motor 29 and to the negative lead *k* of the supply circuit. The motor 29 now receives its current for continuous 120 operation of the motor for the opening of the doors. 125

It is to be noted here that when the fingers or hand which temporarily maintained a switch 48 or the switch 62 closed, is re- 130

- moved from said switch, that is temporarily closed, the circuit is broken through said temporarily closed switch but the motor is in circuit with the supply leads through the energizing of relay 45 and thus the current flows through armature 145 and terminal *h* and wire *d* to the motor connections described. As the motor operates, it drives the sprocket wheel 28 and through chain 24 causes the traveller 23 to move toward the trip 35 on rod 34. Upon the engagement of the finger 123 of traveller 23 with the trip 35, rod 34 is moved longitudinally, thus causing the fingers 37 to throw the switch blade 39 out of engagement with the switch leaves 41, 42 and throwing the blade 38 into contact with the switch leaves 43, 44 which operation breaks the circuit through the motor as well as through the winding of the relay magnet 45 allowing the armature 145 to drop out of engagement with terminal *h*, whereby all operation of the apparatus is stopped and the doors will have arrived at the open position.
- 25 The automatic switch involving the blades 38, 39 when the motor 29 and relay 45 are thrown out of operation as described, conditions the apparatus for the closing operation of the doors. At this time the switch blade 38, it is to be noted, is engaged with the leaves 43, 44 and the switch blade 39 is out of engagement with the switch leaves 41, 42.
- In order to effect the closing of the doors 35, one of the switches 48 is thrown to the closed position or the switch 62 is closed by the insertion of a key into the lock 50 of switch 49 to close the circuit through switch assemblage 62 by turning the key in the direction of the arrow marked "operate" in Figure 7. The temporary closing of the circuit through the normally closed switches 63 and 47 and through a temporarily closed switch 48 or switch 62 and wires *d* and *l*, to switch leaf 43, through switch blades 38 by wire *l*, to the winding of relay magnet 46 and through said magnet to negative supply lead *k*. At the same time current flows from leaves 43 and through switch blade 38 to switch leaves 44 and to wire *j* and through the motor 29 to negative lead *k*. As the motor is thus energized for the closing of the doors, the sprocket 28 is again driven, and therefore, sprocket chain 24, until the finger 123 of traveller 23 engages the trip 135 and again through fingers 37 shifts switch base 36, thereby throwing the switch blade 38 out of engagement with the switch leaves 43, 44 and throwing the switch blade 39 into engagement with the switch leaves 41, 42. As the current is broken at the switch leaves 43, 44, the relay magnet 46 and the motor 29 will be cut out and the doors will have reached their closed position.
- 65 If it should be desired to arrest either the opening or closing movement of the doors at any stage of either the opening or closing movement, one of the normally closed switches 47 is thrown open or the key is inserted in the lock 50 of switch 49 and the key turned in the direction of the arrow marked "emergency stop" which will break the circuit at the switch assemblage 63, said assemblage being normally closed.
- I would state furthermore that while the illustrated example constitutes a practical embodiment of my invention, I do not limit myself strictly to the exact details herein illustrated, since, manifestly, the same can be considerably varied without departure from the spirit of the invention as defined in the appended claims.
- Having thus described my invention, I claim:
1. A device for operating a movable element, said device including a traveller, means to connect said traveller with the element to be moved, an electric circuit, a motor in said circuit, a pair of relay magnets in said circuit, normally open switches 85 optionally operable to close the circuit through either of said switches, an automatic switch including shiftable blades, pairs of switch leaves appurtenant to each blade, each pair adapted to be engaged by one of said blades, wires running from the leaves of one pair and connecting respectively with the corresponding leaves of the other pair, wires connecting the blades with the windings of the respective relay magnets, wire 100 connections adapted to complete circuits through the armatures of each magnet, a wire connecting one switch leaf of one pair with the motor, a wire to complete a circuit through either armature and another switch 105 leaf of a pair, and means to throw said automatic switch by the movements of the traveller in opposite directions, so that when one blade of the automatic switch is engaged with the switch leaves appurtenant thereto, 110 the other of said blades will be disengaged from the switch leaves appurtenant to the last-mentioned blade; together with a switch in said circuit, said switch including two switch assemblages, one of said assemblages 115 being normally closed and the other normally open, and key-operated means optionally operable to close said open switch assemblage or open said closed switch assemblage.
2. A device for operating a movable element, said device including a traveller, means to connect said traveller with the element to be moved, an electric circuit, a motor in said circuit, optionally operative means to temporarily close the circuit, a pair of electromagnets, shiftable switch means, a rod subject to the movement of the traveller in opposite directions for throwing said shiftable switch means, means whereby the wind- 120
- 125
- 130

ing of said magnets will be energized by closing the circuit by said optionally operable means, and means to form circuits through the armatures of said magnets by 5 the energizing of said magnets, the last two means being subject to change of positions of said shiftable switch means; together with means to close a circuit through the motor following the closure of a circuit through 10 one of said magnets.

3. A device for operating a movable element, said device including a traveller, means to connect said traveller with the element to be moved to be operated, an electric circuit, a motor in said circuit, optionally 15 operative means to temporarily close the circuit, a pair of electromagnets, shiftable switch means, a rod subject to the movement of the traveller in opposite directions for throwing said shiftable switch means, means 20 whereby the winding of said magnets will be energized by closing the circuit by said optionally operable means, and means to form circuits through the armatures of said magnets by the energizing of said magnets, the last two means being subject to change 25 of positions of said shiftable switch means.

CLYDE A. CONNELLY.
